GRIP STRENGTH MEASURER

Bo Hjalmar Andersson, Ofelia Nieto 75, Madrid, Spain

Filed Aug. 24, 1972, Ser. No. 283,441

Term of patent 14 years

Int. Cl. D21—02

U.S. Cl. D34—5 K

FIG. 1 is a right side elevational view of a grip strength measurer showing my new design, the left side being a mirror image thereto;

FIG. 2 is a top plan view thereof; and
FIG. 3 is a bottom plan view thereof.

I claim:

The ornamental design for a grip strength measurer, as shown and described.
